UNITED STATES PATENT OFFICE.

JOHN E. KORDICK AND FRANK KORDICK, OF BRIDGEWATER, IOWA.

HAY-CARRIER ATTACHMENT.

1,196,247.

Specification of Letters Patent. Patented Aug. 29, 1916.

Application filed August 16, 1915. Serial No. 45,828.

To all whom it may concern:

Be it known that we, JOHN E. KORDICK and FRANK KORDICK, citizens of the United States, and residents of Bridgewater, in 5 the county of Adair and State of Iowa, have invented a certain new and useful Hay-Carrier Attachment, of which the following is a specification.

The object of our invention is to provide 10 an attachment for hay carriers of simple, durable and inexpensive construction adapted for supporting one end of a rope in such a way as to permit the rope to move without twisting the parts thereof.

15 A further object is to provide an attachment so constructed and arranged as to be readily and easily mounted on a hay carrier of the ordinary type now in use, and adapted to support a rope permitting the 20 end thereof to rotate freely.

A further object is to provide such an attachment so constructed as to tilt slightly for allowing the straight pull on the rope.

Still a further object is to provide such 25 an attachment having a portion adapted to rest on a part of the carrier frame, and arranged to tilt to a limited degree, said attachment having an adjustable portion for limiting the upward movement of the attachment while permitting said tilting motion.

Our invention consists in the construction, arrangement and combination of the 30 parts of the device, whereby the objects contemplated are attained as hereinafter more fully set forth, pointed out in our claims, and illustrated in the accompanying drawings, in which:

Figure 1 shows an end elevation of an 40 attachment for hay carriers embodying our invention. Fig. 2 shows a vertical sectional view through the same taken on the line 2-2 of Fig. 1. Fig. 3 shows a horizontal sectional view taken on the line 3-3 of Fig. 45 2. Fig. 4 shows a side elevation of a hay carrier equipped with an attachment embodying our invention. Fig. 5 shows a top or plan view of a portion of the carrier with our improved attachment installed thereon, 50 viewed from the line 5-5 of Fig. 4. Fig. 6 shows a plan view of a part of a modified form of our device and, Fig. 7 shows a similar view of another part.

In the accompanying drawings we have 55 used the reference numeral 10 to indicate generally a track adapted to be mounted in

a barn or the like. Traveling on the track 10 are rollers 11 of a hay carrier 12, which may be of the ordinary type. Only so much of the hay carrier is shown in the accompanying drawings, as is necessary to illustrate the principle of the operation of mounting our improved attachment on the carrier.

A great many of the carriers now in use 60 have substantially parallel longitudinal frame members 13 extending forwardly and rearwardly from the central portion of the carrier. Between the members 13, at one end thereof is mounted a pulley 14. Ordinarily a rope or flexible device 15 is secured in some way to the other ends of the members 13 and is extended through a pulley 16 for supporting the hay fork over the pulley 14. One of the common difficulties 70 experienced in the operation of the ordinary hay carrier, arises from the fact that when the pulley 16 is in its lowered position and a load is mounted on the hay fork carried by the pulley 16, the rope 15 tends to 75 twist and sometimes so tightly that the load cannot be raised until the rope has been untwisted. This requires lowering the load until it can be reached, or holding it in position until the operator turns the load 80 around untwisting the rope and causing considerable loss of time. Frequently the rope 15 is burned and injured by the friction caused by pulling on the rope while 85 it is twisted. It is our purpose to provide 90 an attachment capable of being mounted on any of the ordinary types of carriers, whereby such twisting of the rope 15 can be avoided.

Our improved attachment can be made in 95 several forms, and as shown in the accompanying drawings, comprises a transverse bar 17, having grooves 18 in its under surface, near its ends adapted to rest on the upper surface of the members 13 near the 100 end thereof opposite the pulley 14. The grooves 18 are curved so as to permit the attachment to tilt in a vertical plane. At the outer ends of the members 17 are downwardly extending lugs or flanges 19, which 105 serve to permit movement of the members 17 laterally of the carrier, and also prevent its jumping off the carrier.

In the form of the device shown in the drawings, a screw threaded bolt 20 is 110 screwed into a suitable central vertical opening in the bar 17, as shown in Figs. 1

and 2. The bolt 20 has a head 21 on its lower end, the upper portion of which forms a ball race member 22. The lower portion of the shank of the bolt 20 is smooth at 20^a. 5 Mounted on the smooth portion 20^a of the bolt 20 is a cylinder 23, closed at its upper end, except for an opening rotatably receiving the bolt 20. The under surface of the end member 24 of the cylinder 23 forms 10 a ball race member coacting with the ball race member 22. Between the ball race members mentioned, are balls 24, whereby the cylinder 23 may rotate freely on the bolt 20.

15 The cylinder 23 is provided, just below the head 21, with an annular shoulder on its interior and against the shoulder just mentioned is mounted an ordinary washer 25. The cylinder 23 is externally screw threaded 20 and is received in the upper end of an internally screw threaded cylinder 26 screwed on to the cylinder 23. The cylinder 26 is provided with a lower end member 27 having an opening 28 to receive the rope 15, extended through the opening 28 and tied in a 25 knot 15^a.

A screw 29 may be extended through the walls of the cylinders 26 and 23 for locking them against relative rotation. A split pin 30 may be extended through the upper end 30 of the bolt 20 above the cross bar 17, if desired, to prevent the accidental removal of the bolt 20 from the bar 17. The bar 17 may be made with parallel projecting lugs 31 shown in Figs. 2 and 3.

Pivotedly mounted on a pin 32 extended through the lugs 31 is a downwardly extending rod 33, the lower end of which is screw threaded and is screwed through a yoke 34, 40 the ends of which are provided with openings 35 which register with each other. The openings 35 are designed to receive a bolt or shaft 36 extended through the arm of the carrier 13, and held in place by a nut 37. 45 It will be seen that the length of the members 33 and 34 may be varied considerably.

In Fig. 6 we have shown a transverse bar of modified form having the central body portion 40 formed with an opening 41 to 50 receive the member 20 and opposite round arms 42 to rest on the members 13. Two bars 43 are each provided with an opening 44 through which an arm 42 is inserted, when the parts are assembled. In the opposite end of each bar 43 is an elongated slot 45 to receive the shaft 36. The arms 43 are mounted outside the members 13 and the elongated slots allow adjustment to fit different carriers.

60 In the practical use and installation of our improved attachment for hay carriers, the balls 24 are placed in the cylinders 23, and the bolt 20 is then inserted therethrough to complete the ball bearing. The bolt 20 is 65 then inserted through the bar 17, and the

pin 30 placed in position. The bar 17 is then mounted on the carrier. The rope 15 is inserted through the opening 28, and the knot 15^a tied in the rope. The cylinder 26 is then screwed on to the cylinder 23, and 70 the screw 29 is placed in position. The yoke 34 is screwed on to the rod 33 until it has reached the proper position, when the pin is inserted through the frame of the carrier and through the opening 35. The device is 75 then ready for use.

It will be noted that the openings 35 are sufficiently large to permit some play of the parts.

When the device is installed it can swing 80 in a vertical plane to a limited degree, permitting a straight pull on the rope 15 between our attachment and the pulley 16.

It will be noted that our improved device may be mounted on practically any carrier 85 having two parallel frame members similar to the members 13, and that it occupies a very small space. The parts which support the rope may be extended downwardly between the frame members.

90 The members 33 and 34 permit the tilting of the attachment and at the same time prevent its jumping upwardly until it might possibly clear the frame members 13 and leave the carrier. The members 33 and 34 95 are longitudinally adjustable, so that they may be fitted to any carrier. In this connection it may be mentioned that the pin 36, in many carriers of ordinary construction, is an axle for an additional pulley, so that our 100 device is adapted for use with carriers as now constructed.

It will be seen that where our improved attachment is used, the rope 15 can turn freely with the parts 24 rotating on the part 105 20^a, and that therefore the portions of the rope 15 above the pulley 16 will not tend to become twisted as might otherwise be the case.

We appreciate the fact that numerous 110 changes may be made in the construction and arrangement of the parts of our improved attachment for hay carriers, and have in fact built our device in several 115 forms, and it is our intention to cover by this application any such changes which may be included within the scope of our claims.

We claim as our invention:

1. An attachment for hay carriers comprising a bar adapted to rest on the carrier frame and to tilt thereon, having downwardly projecting ends to engage such frame and limit endwise movement of said bar, a device for receiving and holding the 120 end of a flexible device mounted on the said bar for rotation.

125 2. An attachment for hay carriers comprising a support adapted to rest on a carrier frame, and to tilt thereon, forming a 130

part of a ball race, a device for receiving and holding the end of a flexible device, forming part of a ball race, rotatably mounted on said support, balls in said race parts, 5 and two part linked adjustable means for limiting the movement of said support with relation to the frame on which it rests.

3. In a device of the class described, a transverse support adapted to rest on the 10 frame members of a hay carrier and to tilt thereon, having downward projections to limit the movement of said support laterally with relation to each carrier, a bolt screwed into said support, having a head below the

support with a ball race in its upper surface, 15 a cylinder closed at its upper end, having said end slidably mounted on said bolt and forming a coacting ball race, balls in said ball races, a cylinder closed at its lower end screwed onto said first cylinder having an 20 opening in said end, and means for locking said cylinders against relative rotation.

Des Moines, Iowa, July 24, 1915.
